(57) **CLAIM**

The ornamental design for a hiking backpack with water bladder as shown and described.

DESCRIPTION

FIG. 1 is a front perspective view of a hiking backpack with water bladder showing my new design;
FIG. 2 is a front elevational view thereof;
FIG. 3 is a back elevational view thereof;
FIG. 4 is a right side elevational view thereof;
FIG. 5 is a left side elevational view thereof;
FIG. 6 is a top plan view thereof;

FIG. 7 is a bottom plan view thereof.
The broken lines depict portions of the hiking backpack with
water bladder that form no part of the claimed design.
